US00D885136S

(12) **United States Design Patent** (10) **Patent No.:** **US D885,136 S**
(45) **Date of Patent:** **** May 26, 2020**

(54) **BEVERAGE CONTAINER**

- (71) Applicant: **Vinglacé, LLC**, Houston, TX (US)
(72) Inventor: **Colton Bryan Haas**, Houston, TX (US)
(73) Assignee: **Vinglacé, LLC**, Houston, TX (US)
(**) Term: **15 Years**
(21) Appl. No.: **29/720,208**
(22) Filed: **Jan. 10, 2020**
(51) LOC (12) Cl. **07-01**
(52) U.S. Cl. **USPC D7/531; D7/530**
(58) **Field of Classification Search**
USPC D7/517, 519, 510, 511, 523, 532, 300,
D7/300.1, 313, 529, 530, 531, 392.1,
D7/396.2; D9/500, 501, 502, 503, 504,
D9/516, 530, 539, 549, 562, 571, 574,
D9/575, 453, 435, 436, 443, 449, 454
CPC A47G 19/22; A47G 19/2288; A47G
19/2205; A47J 43/27; A47J 41/0077;
A47J 41/0088

(57) **CLAIM**

The ornamental design of a beverage container, as shown and described.

DESCRIPTION

FIG. 1 is a front perspective view of a beverage container showing my new design;

FIG. 2 is a bottom perspective view of the beverage container of FIG. 1;

FIG. 3 is a left side view of the beverage container of FIG. 1;

FIG. 4 is a right side view of the beverage container of FIG. 1;

FIG. 5 is a rear view of the beverage container of FIG. 1;

FIG. 6 is a front view of the beverage container of FIG. 1;

FIG. 7 is a top plan view of the beverage container of FIG. 1; and,

FIG. 8 is a bottom plan view of the beverage container of FIG. 1.

The broken lines in the drawings depict portions of the beverage container that form no part of the claimed design.

1 Claim, 7 Drawing Sheets
